PIEZO-ELECTRIC DEVICE

Application filed June 10, 1928, Serial No. 286,571, and in Germany June 24, 1927.

The present invention has for its object a device for automatic maintenance of the constancy of the frequency of electrical oscillatory circuits with the help of the so-called piezoresonators, as have been employed lately in high-frequency-engineering for different purposes. Such crystals are suitable to maintain automatically on a constant value as desired the frequency of an oscillatory circuit which frequency in consequence of any external influences, is subject to fluctuations. Difficulties, however, arise in that the crystals employed, with the devices so far in use, were exposed to high tensions, as they had to be connected in parallel with the entire self-inductance or capacity of the oscillatory circuit. The crystals are, however, extremely sensitive to high tensions, and may easily be destroyed by them.

In accordance with this present invention the crystals are only coupled with a part (a fractional portion) of the inductance or capacity of the oscillatory circuit. This ensures that the crystal will only be exposed to a portion of the full voltage prevailing in the syntonization circuit.

The invention is more fully set forth by the following detailed description taken with reference to the accompanying drawings, which show diagrammatically some practical embodiments of the invention.

Fig. 1 is a high frequency circuit having a piezo-electric crystal device associated therewith in accordance with this invention.

Fig. 2 is a similar circuit having the crystal connected in a different way, and

Fig. 3 is a combination of the arrangements according to Figs. 1 and 2, employing two crystals, whereby a combined and improved action as compared to the arrangements of Figs. 1 and 2 is obtained.

Similar reference characters refer to similar elements in the individual figures.

Referring to the drawings, L is an inductance of an oscillatory circuit and C₁, in series with C₂, forms the capacity of the circuit. This circuit may be the oscillatory circuit of a discharge device or a vacuum tube generator G producing a negative re-

sistance characteristic between two of its electrodes which are connected to the points a and b of the circuit shown in the drawing. As is well known, in this case electric oscillations will be maintained in the circuit L, C₁ and C₂ having a frequency determined by the natural frequency of the circuit. As practical experiments have shown and as may be proved by theoretical analysis, the frequency of the oscillations may be furthermore effected by the value of the negative resistance of the tube, i. e., steepness of the negative slope of its resistance characteristic. This latter is subject itself to variations due to the variations of heating current, anode voltage or other supply sources. Therefore, these variations will produce corresponding frequency changes. In my invention I provide a piezo-electric device to compensate for these variations and to minimize these frequency changes.

Furthermore, the capacities C₁ and C₂ may be themselves subject to variations. For example, one of them may be the antenna capacity which varies its value on account of mechanical movements, such as swinging by the wind, or on account of changes in the surrounding objects, atmosphere, etc.

These capacity changes of the antenna are of great disadvantage, especially in the case of very short waves in that minute deviations from a normal value will cause corresponding frequency changes of the waves radiated and consequent detuning and distortion of signals. According to the invention, a piezo electric crystal K₁ is placed parallel to the capacity C₁. The capacities C₁ and C₂ are of such differing value that the larger amount of voltage drop is taken up by the capacity C₂ which has a small capacity value as compared to that of the capacity C₁.

Thus, the voltage drop across C₁ is low enough to secure a reliable operation of the crystal K₁. If the crystal has a natural frequency f₁ equal to the desired frequency f to be maintained, it will have no influence under normal conditions and will act only as a high resistance. If, however, the frequency (f) increases, even by

a slight amount relative to the natural frequency f_1 of the crystal, the crystal K_1 will instantaneously present a comparatively high capacitative impedance, as has been stated above. The resultant capacity C of the circuit may then be calculated by the formula

$$\frac{1}{C} = \frac{1}{C_1} + \frac{1}{C_1 + K}$$

where K is the capacitative impedance of crystal K_1 . This shows that the resultant capacity is decreased by the comparatively large influence of K_1 , so that there is a tendency to maintain the original frequency. In case the frequency is decreased similar consideration would show that the crystal acts in the opposite direction tending to maintain the frequency at its normal value. (See 20 Cady, Vol. X, page 83, Proceedings Institute of Radio Engineers, 1922.)

Referring to Fig. 2 the same effect is obtained as in Fig. 1 by placing a crystal K_2 in parallel with a suitable part (fractional 25 portion) of the inductance L of the oscillatory circuit. The crystal is connected galvanically, as in the drawing, or inductively by an induction coil. If in this case the frequency f decreases with respect to normal 30 frequency f_2 of the crystal to be maintained, then the crystal K_2 will present an impedance equivalent to that of an inductance whereby the resultant inductance L is decreased, i. e., the natural frequency increased. Thus there is a tendency to maintain the original frequency.

According to the arrangement of Fig. 3, which is a combination of Figs. 1 and 2, both crystals K_1 and K_2 are provided where- 40 by a combined and improved action is obtained, as may be readily understood. It is not essential, of course, that the piezo electric device be connected in the specific manner therein shown in the drawings, but it 45 may be arranged in any suitable manner to effect the natural constants of the oscillatory circuit in order to bring about the effect described without departing from the scope of the present invention as stated in the ap- 50 pended claims.

The circuit shown in the drawing may represent the oscillatory circuit of any circuit arrangement and is not restricted to the arrangements specifically referred to above. 55 It may, for instance, be the anode circuit of a self-oscillating vacuum tube oscillator using a reaction between anode and control circuit, in which case the crystal will act to keep constant the frequency of oscillations 60 independent of outside influences.

Claims:

1. A high frequency electric circuit including inductance and capacity elements and carrying currents having a frequency 65 determined by said inductance and capacity

elements, a piezo-electric crystal device having a natural frequency equal to a frequency to be maintained in said circuit, and placed in parallel relationship to a fractional part of one of said elements so as to be exposed to less than the full voltage of the circuit and adapted to vary its impedance presented to said currents in such a manner as to compensate for variations of said inductance and capacity elements to maintain the natural frequency of said circuit.

2. A high-frequency electric circuit including inductance and capacity and carrying currents having a frequency dependent on the natural frequency of said circuit, a piezo-electric crystal device having a natural frequency equal to the frequency to be maintained in said circuit and arranged in parallel with a fractional portion of the capacity in said circuit so as to be exposed to less than the full tension of the full circuit capacity and adapted to change the resultant capacity of the circuit capacity element and crystal combination in such a manner as to tend to maintain the natural frequency of said circuit.

3. A high-frequency electric circuit including inductance and capacity elements and carrying currents having a frequency dependent on the natural frequency of said circuit, a piezo-electric crystal device having a natural frequency equal to the frequency to be maintained in said circuit and placed parallel to a capacity element in the circuit, and a second piezo-electric crystal device placed parallel to an inductance element in the circuit, said crystals being adapted to change the effect of said capacity and inductance elements in such a manner as to tend to maintain the natural frequency of said circuit.

In testimony whereof I have affixed my signature.

WALTER HAHNEMANN.
